The P. S. Sonnen Agency for Patents.

William & R. P. Resor. Cincinnati: Ohio
Letters Patent Design No. 98) dated Oct 10th 1847

The schedule referred to in these Letters Patent and making part of the same.

To all whom it may concern: Be it known; That we William Resor, and R. P. Resor, of the City of Cincinnati, in the State of Ohio, have invented and produced a new useful Design for an ornamental Vase, to be cast in iron or other metal, the immediate object of which is to use the same as a stove for the heating of apartments by the combustion of coal; which when so used we denominate the Grecian Vase Stone, and we do hereby declare that the following is a full and exact description thereof & of the ornaments thereon.

In the accompanying drawing the form & design are fully exhibited.

Around the bottom of the Pedestal A, there is a border of ornamental leafing B, and on its upper edge the border C; The lower portion of the vase, immediately above the pedestal has the form and the ornamental leafing D, the respective members of this part being such as are represented. The Swelled part, or body has the ornamental leafing E, & F; and above this part it is fluted, as shown at G, and above this fluted part is the upper rim, or border of wrought work, as shown at H.

Having thus fully described and represented in the accompanying drawing, the shape or configuration of our Vase, & of the disposition of the various ornaments with which we embellish the same, what we claim as new therein, & desire to secure by letters patent, is the particular shape or configuration of said vase, having on it the respective members, and ornamental devices arranged & combined as represented.
